PACKAGE FOR COOKIES OR THE LIKE

Hugh R. Weiss, Montclair, N.J., assignor to The Pantasote Company, Passaic, N.J., a corporation of New Jersey

Filed Sept. 28, 1964, Ser. No. 31,898

Term of patent 14 years

(Cl. D58—2)

I claim:

The ornamental design for a package for cookies or the like, as shown.
